UNITED STATES PATENT OFFICE

THOMAS CAHILL, OF ARDMORE, PENNSYLVANIA, ASSIGNOR TO NEWTON & THOMPSON MANUFACTURING COMPANY, OF BRANDON, VERMONT, A CORPORATION OF VERMONT

STEEL-WOOL HOLDER

Application filed June 4, 1929. Serial No. 368,354.

This invention relates to a holder for steel wool, and more particularly to such a holder for use in scouring cooking utensils and the like.

- Steel wool or like abrasive material is eminently suitable for scouring cooking utensils, but is very annoying, if not actually dangerous, to use, owing to the tendency of the steel wool fibres to prick into the hands of the user.
- 10 It has heretofore been suggested to use a steel wool holder for the purpose of preventing such injury, and the primary object of the present invention is to provide a different form of steel wool holder which is better, simpler, and cheaper than other steel wool holders now known. My invention may utilize some or all of such elements as a handle, a protective flange or apron for protecting the hands of the user, fastening means for holding a body or pad of steel wool on the holder, and a projection or buffer for preventing the fastening means from scratching or otherwise injuring the surface being cleaned. The fastening means, in accordance with my present invention, consists essentially of hook means positioned around the projection or buffer, and preferably of hook means extending spirally around the peripheral wall of the projection or buffer.
- 20 A further object of my invention is to provide a very secure gripping action upon the steel wool, and this I do by compressing an annular portion thereof between the hook means and the wall of the said projection or buffer, the hook means being so shaped as to attain this result, and so mounted as to permit of a relatively uniform distribution of the gripping pressure on the steel wool.

To the accomplishment of the foregoing and such other objects as will hereinafter appear, my invention consists in the holder and fastening elements, and their relation one to the other, as hereinafter are more particularly described in the specification and sought to be defined in the claims. The specification is accompanied by a drawing in which:

- Fig. 1 is an elevation of one form of my invention;
- 50 Fig. 2 is a perspective view of the same

form of the invention with the pad of steel wool removed;

Fig. 3 is a partially sectioned elevation of a modified form of the invention;

Fig. 4 is a bottom view thereof;

Fig. 5 is a section taken in the plane of the line 5—5 in Fig. 3;

Fig. 6 is a bottom view of a holder having a modified hook arrangement; and

Fig. 7 is an elevation thereof, the apron being removed in both Figs. 6 and 7.

Referring to the drawing, it will be seen that in each case the holder consists of a body member having a handle A at one end thereof, a projection or buffer B at the other end thereof, a flange or apron C intermediate the handle A and the projection B, and fastening means D for anchoring a body or pad of steel wool E to the holder. In general, the fastening means consists of one or more hook elements distributed around and outside of the walls of the projection or buffer.

Referring now more particularly to the form of the invention illustrated in Figs. 1 and 2 of the drawing, the handle A, projection B, and flange C, are all formed integrally out of a single body of material, preferably, a moderately hard rubber, while the fastening means D consists of a spiral spring wire hook which extends around but is spaced from the walls of the projection B. The hook is held to the body of the holder by a relatively straight portion 2 of the hook wire, only one end thereof being visible, which straight portion is fitted in a transverse or diametrical hole drilled through the projection or buffer B near the face of the flange C. In the particular case here shown the spiral hook is one and one-half turns in length, but this, obviously, may be varied.

Figs. 3, 4, and 5 illustrate a modification of the invention, the manufacturing cost of which is greatly reduced by making the apron C separately from the body member of the holder. The latter in this case is preferably turned out of wood, and consists of a handle A at one extremity thereof, a projection or buffer B at the other extremity thereof, and a recessed portion 4 intermediate the handle and projection. An apron C,

which preferably is an annular disc of flexible rubber, is pulled over the handle A and rests in the recessed portion 4, the resulting flange or apron guarding the fingers and hand of the user during the scouring operation, and yet permitting pressure to be applied thereto directly and over a considerable working area.

The fastening means in this modification 10 comprises a bent spring wire having a straight portion 6, which preferably is reciprocably mounted in a diametrically drilled hole 8 in the projection, and a spiral hook portion 10, which extends around the circumferential wall of the projection for approximately one turn. The reciprocity of the hook is indicated by the broken line position thereof shown in Fig. 4. The wall of the buffer is grooved, as at 12, in order to 20 help the hook hold the steel wool.

The fastening means is suitably bent and mounted to obtain a very effectual and evenly distributed gripping action on the abrasive pad. When the hook is first turned into the 25 pad of steel wool the end of the hook tends to spring away from the wall of the projection or buffer. When the hook has been turned about half a revolution into the steel wool, the straight portion 6 slides within the 30 opening 8, permitting the hook to assume a position somewhat as is indicated in the broken lines except that the point of the hook will be sprung outwardly. This permits a considerable body of steel wool to be caught 35 between the hook and the wall of the projection. As the rotation of the holder is completed the body of steel wool initially caught 40 between the hook and the projection tends to force the hook back to the position shown in full lines, thereby gripping the steel wool tightly at the opposite portion of the periphery of the projection. From another viewpoint, it may be stated that the reciprocable 45 mounting of the straight portion 6 in the hole 8 permits the hook to readjust itself automatically to that compromise position which insures the most even distribution of pressure on the steel wool.

Attention is now directed to the modification 50 of the invention illustrated in Figs. 6 and 7. In these illustrations the flange or apron C has been omitted, but it will be understood that in actual use such an apron may be slipped over the handle A and onto the recessed portion 4 in a manner similar to that employed with the preceding modification. The present form of the invention differs from that already described in employing two semi-circular hooks 20 and 22, formed at 55 opposite ends of a straight portion 24. Here too the straight portion is preferably made reciprocable in the transverse diametrical hole 26 of the projection or buffer B, thereby permitting the two hooks to readjust themselves for a most even grip on the body of the

steel wool. As before, the device is prepared for use by pushing the projection B into the middle of a body of steel wool, and thereafter rotating the handle in order to cause the hooks to thread themselves into the steel 70 wool.

It should be observed that in all of the forms of the invention the fastening means includes one or more hook means positioned outside of the end of the holder, and that the end of the holder is preferably made to constitute a projection which projects beyond the fastening means in order to prevent the latter from scratching the surface being scoured when the pad of abrasive material becomes considerably worn away. Also, the walls of the projection form an abutment 75 against which the fastening means clamp the center portion of the pad.

If the hook has a number of turns, as in 80 the first modification described, it may be drawn somewhat deeply into the steel wool pad, as is indicated by the dotted lines in Fig. 1. Even if this brings the end of the hook 85 below the face of the projection no damage is apt to result because during use the pad is compressed, and the spiral hook will likewise be compressed nearer to the face of the flange, and therefore be brought within the end of the projection or buffer. The latter, 90 of course, is made at least sufficiently long to accommodate the spiral hook when the latter is compressed toward the flange.

The construction, the mode of operation, and the advantages of my present steel wool 95 holder will for the most part be apparent 100 from the foregoing description. It will be understood that any pad may be used, as well as steel wool, for any kind of polishing or 105 finishing operation, as well as for scouring. It will also be apparent that while I have 110 shown and described my invention in the preferred form, many changes and modifications 115 may be made in the structure disclosed without departing from the spirit of the invention, 120 defined in the following claims.

I claim:

1. A holder for steel wool comprising a flanged handle, a projection projecting on the side of said flange opposite the handle, and wire hook means inwardly spaced from the end of and positioned around the projection, the projection preventing contact of the hook means with the surface being abraded.

2. A holder for steel wool comprising a flanged handle, a cylindrical projection projecting on the side of said flange opposite the handle, and spiral wire hook means positioned circumferentially around the projection.

3. A holder for steel wool comprising a flanged handle, a cylindrical projection projecting on the side of said flange opposite the handle, and spiral wire hook means spaced

from the end of and positioned circumferentially around the projection, the projection preventing contact of the hook means with the surface being abraded.

4. A steel wool holder comprising a body member, shaped to form a handle at one end of the member and a projection at the other end of the member, said member being recessed intermediate said handle and projection, a disc-shaped protective apron fitted into said recess, and wire hook means positioned around said projection.

5. A steel wool holder comprising a body member shaped to form a handle at one end of the member and a projection at the other end of the member, said member being recessed intermediate said handle and projection, a disc-shaped protective apron fitted into said recess, and wire hook means extending spirally around said projection.

6. A steel wool holder comprising a body member shaped to form a handle at one end of the member and a projection at the other end of the member, said member being recessed intermediate said handle and projection, a disc-shaped protective apron held in said recess, and bent wire fastening means comprising a straight portion passing diametrically through said projection and a hook portion extending spirally around the wall of said projection.

Signed at New York, in the county of New York and State of New York, this 31st day of May A. D. 1929.

THOMAS CAHILL.
